(57) **CLAIM**

The ornamental design for an exercise device, substantially as shown and described.

DESCRIPTION

FIG. 1 is a top, rear perspective view of a first embodiment of an exercise device

FIG. 2 is a front view of the exercise device of FIG. 1

FIG. 3 is a rear view of the exercise device of FIG. 1

FIG. 4 is a left side view of the exercise device FIG. 1

FIG. 5 is a right side view of the exercise device of FIG. 1

FIG. 6 is a top view of the exercise device of FIG. 1

FIG. 7 is a bottom view of the exercise device of FIG. 1

FIG. 8 is a top, rear perspective view of a second embodiment of an exercise device

FIG. 9 is a front view of the exercise device of FIG. 2

FIG. 10 is a rear view of the exercise device of FIG. 2

FIG. 11 is a left side view of the exercise device FIG. 2

FIG. 12 is a right side view of the exercise device of FIG. 2

FIG. 13 is a top view of the exercise device of FIG. 2

FIG. 14 is a bottom view of the exercise device of FIG. 2

FIG. 15 is a top, rear perspective view of a third embodiment of an exercise device

FIG. 16 is a front view of the exercise device of FIG. 3

FIG. 17 is a rear view of the exercise device of FIG. 3

FIG. 18 is a left side view of the exercise device FIG. 3

FIG. 19 is a right side view of the exercise device of FIG. 3

FIG. 20 is a top view of the exercise device of FIG. 3; and, FIG. 21 is a bottom view of the exercise device of FIG. 3. The dashed lines form no part of the claimed design.

1 Claim, 18 Drawing Sheets
